UNITED STATES PATENT OFFICE.

NELSON L. JARVIS AND FRANK J. JARVIS, OF PALMER, MASSACHUSETTS.

SERVICE WAGON.

Application filed November 8, 1922. Serial No. 599,679.

To all whom it may concern:

Be it known that we, NELSON L. JARVIS and FRANK J. JARVIS, citizens of the United States, residing at Palmer, in the county of 5 Hampden and State of Massachusetts, have invented certain new and useful Improvements in Service Wagons, of which the following is a specification.

This invention relates to improvements in 10 service wagons or carts of the type used for hotel maid service or similar purposes, and has particular reference to improved means for covering the trays on said carts.

The principal object of the invention is 15 to provide a cover for the cabinet on the service wagon whereby the same may be made to extend out and cover the cabinet or may be folded up and stood up out of the way when the cabinet is opened for 20 use.

Another object of the invention is to provide an easel type of cover which may be quickly closed and folded down on the cabinet as an ordinary cover, or may be 25 folded and stood up as an easel out of the way while the cabinet is in use.

Other objects and advantages of the invention should be readily apparent by reference to the following specification taken 30 in connection with the accompanying drawings, and it will be understood that any modifications or departures may be made from the specific features disclosed within the scope of the claim without departing 35 from or exceeding the spirit of the invention, the preferred form only being shown for sake of illustration.

Figure I represents a front view in elevation of a cart embodying the invention.

Figure II represents a top or plan view of Figure I.

Figure III represents a fragmentary perspective view of the cabinet and cover, the cover being folded up out of the way in 45 its open position.

Figure IV represents a fragmentary side view showing in full lines the cabinet partially opened and in dotted lines the position of the cover when opened.

Prior to this invention considerable difficulty has been experienced with the covers of the top trays of wagons of this nature. They were ordinarily one leaf hinge covers, which covers were decidedly in the way 55 when the cabinet was opened, as if opened

up flat they would extend out beyond the side of the wagon, being a menace to surrounding objects with which the wagon was likely to come in contact, and being in the way of the operator. If it was held in a vertical position it would slam down and catch the hands or fingers of the operator. If left in closed position it had to be opened each time anything was put into or taken out of the cabinet, making a slow and awkward arrangement.

It is, therefore, the object of the present invention to provide means overcoming these difficulties and to provide a cover cheap of construction and efficient in operation, that can be opened up and stowed out of the way quickly without danger of collapsing and without danger to surrounding objects.

Figure I shows a front elevation of a service wagon provided with these improvements. This wagon in question is provided with the wheels 1, the shelves 2, the top cabinet or tray 3, and the side bags 4.

Figure II shows the top or cover of the tray or cabinet 3. In this particular cabinet the cover is made of two leaves 5 and 6 hinged together at 7. There is also a permanent or fixed narrow section 9 to which the cover is hinged by the hinges 8. It will be noted in Figure IV that the front section 5 is so hinged as to fold down on the second section 6, but that the section 5 rests on a post 10 secured to the second section 6. Fastened to the top of this post 10 is a rubber plug 11 on which the leaf 5 rests.

The operation of this cover can be readily understood from Figure IV. It will be noted that the first section 5 is swung over on its hinges 7 so that it lies on top of the rubber section 11 of the post 10. Then the two sections 5 and 6 together are rotated on the hinge 8 securing the second section 6 to the permanent strip 9 until it takes the position of the dotted lines or stands up on the permanent strip 8 like an easel, which is shown in perspective in Figure III. It will readily be seen from Figure III that when the cover is so folded up, it is out of the way, allows of ready access to the top cabinet, has no tendency to fall shut, and has no tendency to fall over beyond the sides of the wagon or to close the tray. To close the tray the reverse of the operation only is necessary; the two sections together are

swung down on the hinge 8 and the section 5 is swung over on the hinge 7 until it lies flat, as shown in Figure II.

From the foregoing description it will be seen that we have provided a simple and efficient means for providing a cover to the top tray, which cover may be quickly and easily folded up and stowed out of the way when the tray is in use and readily folded down to act as a protective cover when the tray is not in use.

We claim:

In a device of the character described, a wagon body portion, a tray thereon, and a cover for the same, comprising a plurality of leaves hinged together, a fixed portion supported by the tray at one side thereof

and to which one of the leaves is hinged, and a post fixed on the leaf adjacent its hinge connection to the fixed portion, said post extending outwardly from the leaf to which it is fixed to a distance whereby it will engage a second leaf of the cover when it is folded back on its hinge to the first leaf and hold the second leaf spaced from the first in all positions of the first leaf on its hinge to the fixed portion and insure contact between the edge of the spaced leaf and the fixed portion to support the leaves in upright position when moved to contact position on the hinge uniting the first leaf and the fixed portion.

NELSON L. JARVIS.
FRANK J. JARVIS.
